United States Patent Office.

L. H. COBBS, OF MONTGOMERY, ALABAMA.

Letters Patent No. 93,415, dated August 10, 1869.

IMPROVEMENT IN SEWING-MACHINE.

The Schedule referred to in these Letters Patent and making part of the same.

To all whom it may concern:

Be it known that I, L. H. COBBS, of Montgomery, in the county of Montgomery, and State of Alabama, have invented a new and useful Improvement in Sewing Machines; and I do hereby declare that the following is a full, clear, and exact description thereof, which will enable others skilled in the art to make and use the same, reference being had to the accompanying drawings, forming part of this specification.

The object of this invention is to provide improvements in the construction of the Grover and Baker sewing-machine, whereby the "lost motion" due to the wear of the crank-connection with the needle-arm, also the lost motion of the operating-device for the vertical shaft of the curved needle may be avoided.

Figure 1 represents a side view of my improvement, which consists of an adjusting-attachment to the needle-arm, which latter, together with the table and spiral post of the curved needle, are shown in red outline.

Figure 2 represents a plan view of the same.

Similar letters of reference indicate corresponding parts.

In the common construction of these machines, the crank-pin A works in a slot in the end of that part of the needle-arm B which is under the table, and the oscillating motion of the spiral post C, which carries the curved needle, is also imparted by the walls of a vertical slot in an extension of the needle-arm. The walls of these slots, and also the crank-pins and spiral shafts, wear away from long use, and become so loose as to work badly.

To remedy this, I propose to introduce adjustable plates, D D', in the slot for the crank-pin, and the adjustable plates E E' in the extension, for operating the spiral shaft.

To operate the said adjustable plates D D', I pro-

vide the screws F G, and jam-nuts H. The screws F pass loosely through the wall, I, of the slot, and the plate D' screwing into the plate D, and against the inner face of the wall K. The screws G are tapped through the wall I, and press upon the side of the plate D'.

The crank-pin A, working between these plates, may be always made to work snugly, by adjusting the plates to take up any wear that may occur.

The manner of adjusting the plates will be readily seen by inspection of the drawing.

The same arrangement of adjusting-plates and screws may be applied in the slot of the extension L, for operating the post C, but I prefer to dispense with the rigid walls of the slot, and employ the adjustable plates E E', arranged to work laterally in grooves, M, so that when adjusted closely to the post, they will be self-adjusting as a whole relatively to the extension L, wherein they are supported, and thereby avoid lateral strain, which would occur if the shaft were slightly out of the vertical line, or if it be not exactly in the centre of the slot.

These plates are adjusted to or from each other by the screws N and jam-nuts O, the said screws passing loosely through the plates E, and screwing into the plates E'.

Having thus described my invention, I claim as new, and desire to secure by Letters Patent—

The combination, with the needle-arm B and crank-pin A, or oscillating needle-post C, of the plates D and D', or E and E', and their adjusting-screws and nuts, substantially as described.

L. H. COBBS.
